UNITED STATES PATENT OFFICE.

LOUIS DREVON, OF PONT-DE-BEAUVOISIN, FRANCE.

BOTTLE-STOPPER FOR AERATED BEVERAGES.

SPECIFICATION forming part of Letters Patent No. 654,959, dated July 31, 1900.

Application filed April 2, 1900. Serial No. 11,128. (No model.)

To all whom it may concern:

Be it known that I, LOUIS DREVON, a citizen of the Republic of France, residing at Pont-de-Beauvoisin, (Savoie,) France, have 5 invented certain new and useful Improvements in Bottle-Stoppers for Aerated Beverages, of which the following is a specification:

My invention relates to bottle-stoppers for use with aerated beverages, and has for its 10 object to provide a stopper whereby the operation of bottling is facilitated without loss of gas of the liquids, while the rapidity with which the reclosing of the stopper can be effected prevents the loss of gas which takes 15 place each time it is removed.

In order that my invention may be readily understood and carried into effect, I will describe the same fully with reference to the accompanying drawings, in which—

20 Figure 1 shows a vertical central section of a bottle-stopper constructed in accordance with my invention, and Fig. 2 a modified construction of the same. Fig. 3 shows in elevation and plan an appropriate device for use 25 in connection with my improved stopper, whereby a portion of the contents of the bottle may be abstracted without entirely removing the stopper from the bottle.

Referring more particularly to Fig. 1, the 30 main portion R of the stopper is constructed of porcelain, glass, metal, or other suitable material and is provided with a central vertically-disposed aperture S, terminating into a flared opening A at the top of the stopper, 35 and is contracted near the top to form a shoulder or valve-seat S', which is engaged by a ball-valve B, preferably of caoutchouc or the like. This ball is constantly pressed against the narrow opening at the top by 40 means of a helical spring C, which rests upon a pin D, arranged in the stopper at the lower portion thereof. A rubber ring or band E covers the apertures of the passage in which the pin D is located, and thus also insures a 45 tight fit between the mouth of the bottle and the stopper.

I may, if found desirable, provide a flexible washer F above the valve B, as shown in Fig. 2, so that by means of the internal pressure, combined with that of the ball, the outlet may be more completely closed.

The stopper is secured to the neck of the

bottle by means of a suitable galvanized wire or other device, such as is now commonly in use in connection with stoppers for beer-bottles. Preferably, however, I employ the arrangement shown in Figs. 1 and 2, whereby the perforation of the stopper is obviated. To this end this latter is formed at its upper portion with an annular recess or groove G, 60 around which a wire is passed having diametrically-opposed loops to engage an ordinary wire lever.

In order to fill the bottle, it is only necessary to slightly open the vertical central aperture S by depressing with the aid of the filling-nozzle the valve B or washer F. The liquid then enters the bottle, and after having filled the same the pressure from the nozzle against the ball is released, so as to allow 70 the spring C to press the valve tightly against its seat, so forming a close and hermetic joint.

When it is desired to remove the entire contents of the bottle, the stopper is swung to one side in the manner usual with beer-bottles furnished with such lever-stoppers. The closing of the bottle is effected by reversing the operation. By the use of my improved stopper it is possible to empty the bottle or remove any portion of the contents 80 thereof without entirely removing the stopper. This may be effected while the bottle is in an inverted position by exerting pressure against the closing-valve for the whole time during which it is desired to remove any portion of the contents. This result may be obtained by the aid of the spring-presser (shown in Fig. 3) or by any other convenient means. If the said spring-presser be employed, it is placed across a glass or other vessel and the 85 elastic valve of the stopper is depressed by the projection H, when the liquid will at once be projected into the glass. As soon as sufficient liquid has been poured out the down pressure is released and the stopper closes 90 automatically without having permitted the gas to escape owing to the inverted position.

What I claim is—

1. In a bottle-stopper, the combination of the main portion R provided with a centrally-arranged vertical opening and a horizontally-extending recess, a valve-seat arranged in the said vertical opening, a spring-actuated valve adapted to engage said seat, means

mounted in said horizontal recess for supporting said valve and a flexible band surrounding the stopper and inclosing said horizontal recess, substantially as described.

5 2. In a bottle-stopper, the combination of the main portion R provided with a centrally-arranged vertical opening and a horizontally-extending recess, a valve-seat arranged in the said vertical opening, a spring-actuated valve adapted to engage said seat, a pin arranged in the said horizontal recess to support said valve, and a band surrounding the said stopper inclosing the said recess, substantially as described.

10 3. In a bottle-stopper, the combination of the main portion R provided with a centrally-arranged vertical opening and a horizontally-

extending recess, a valve-seat arranged in said vertical opening near the top thereof, a flexible washer adapted to engage the said seat, a 20 spring-pressed ball-valve adapted to engage said washer for closing said vertical opening, a pin arranged in the horizontal recess for supporting the said valve, and a band surrounding the said stopper inclosing said horizontal recess, substantially as described. 25

In testimony whereof I have hereunto set my hand, in presence of two subscribing witnesses, this 8th day of March, 1900.

LOUIS DREVON.
